UNITED STATES PATENT OFFICE.

WILLIAM E. BRAY, OF COLFAX, WASHINGTON.

WRAP-HOLDER FOR CHAIRS.

1,119,396.

Specification of Letters Patent.

Patented Dec. 1, 1914.

Application filed December 2, 1913. Serial No. 804,246.

To all whom it may concern:

Be it known that I, WILLIAM E. BRAY, a citizen of the United States, residing at Colfax, in the county of Whitman and State 5 of Washington, have invented a new and useful Wrap-Holder for Chairs, of which the following is a specification.

The device forming the subject matter of this application is a hanger or support, 10 adapted to be applied to the back of a bench or chair, the device being employed, primarily, in places of public assembly, for the purpose of supporting garments.

The invention aims to provide a device of 15 the type above described which may be connected with a seat of any sort, without mutilating the same.

Another object of the invention is to provide a device of the type above indicated 20 which will not unduly obstruct the passage way between rows of seats, when in use.

It is within the scope of the invention to improve generally and to enhance the utility of, devices of that type to which the present 25 invention appertains.

With the above and other objects in view which will appear as the description proceeds, the invention resides in the combination and arrangement of parts and in the details of construction hereinafter described 30 and claimed, it being understood that changes in the precise embodiment of the invention herein disclosed can be made within the scope of what is claimed without departing 35 from the spirit of the invention.

In the accompanying drawing:—Figure 1 shows the invention in front elevation; Fig. 2 is an end elevation, the bail being in depending position; Fig. 3 is an end elevation, 40 the bail being uplifted; Fig. 4 is a fragmental top plan showing the end portion of one of the standards whereunto the bail is pivoted.

In carrying out the invention there is provided a back plate 1 which may constitute a 45 part of a bench or chair. Standards 2 are provided, the same constituting parts of plates 3 secured to the element 1 by means of screws 4 or in any other suitable manner. 50 Adjacent its outer end, each standard 2 is thinned to form a tongue 5, defining shoulders 6 in the standard.

A bail is provided, the same comprising an intermediate portion 7 and arms 8, the arms 55 8 being provided with slots 9 defining extensions 10. The tongues 5 of the stand-

ards 2 are received in the slots 9 and the extensions 10 of the bail lie upon opposite sides of the tongues. The extensions 10 of the bail and the tongues 5 are connected by pivot element 12. The shoulders 6, adjacent their upper ends are cut away as indicated at 12. The upper edge of the back plate 1 may be inclined as indicated at 14 and the lower edge of the back plate may be inclined 65 as indicated at 15. The intermediate portion 7 of the bail lies below the lower edge of the plate 1.

In practical operation, when the bail is in a depending position as shown in Fig. 2, 70 the extensions 10 of the bail will abut against the shoulders 6, and the bail will be prevented from swinging inwardly. Owing to the fact that the lower edge of the element 1 is beveled as indicated at 15, ample space 75 will be provided for the garments which are mounted upon the bail. The bail, therefore, will not be crowded outwardly by the garments, and will not obstruct the passageway between the seats, it being noted that since 80 the intermediate portion of the bail lies below the lower edge of the element 1, ample space for the garments will be afforded.

The bail ordinarily hangs in a depending position as shown in Fig. 2, but owing to 85 the fact that the shoulders 6 are cut away adjacent their upper ends as shown at 12, when the bail is swung upwardly and rearwardly as shown in Fig. 3, the intermediate portion 7 of the bail lies adjacent the inclined surface 14 of the member 1, and the surface 14 serves to guide the finger of the operator into engagement with the intermediate portion of the bail.

Having thus described the invention, what 95 is claimed is:—

A garment support for seats, comprising a back plate having a downwardly and forwardly inclined upper edge; standards projecting from the back plate, the standards 100 being thinned at their outer ends to form tongues and to form shoulders at the sides of the tongues; a bail; pivot elements uniting the ends of the bail and the tongues, the bail being adapted to hang in a depending 105 position and being adapted to be swung upwardly and rearwardly into abutment with the back plate, the lower portions of the shoulders being disposed parallel to the back plate to hold the bail in spaced relation to the back plate when the bail is in a depending position, the upper portions of

the shoulders being rearwardly inclined to permit the bail to rest against the back plate adjacent the bottom of said inclined edge when the bail is swung upwardly and rearwardly, whereby the bail will be prevented from exerting a leverage upon the pivot elements and the thinned portions of the standards, with the shoulders as a fulcrum.

In testimony that I claim the foregoing as my own, I have hereto affixed my signature in the presence of two witnesses.

WILLIAM E. BRAY.
